BUTTER WARMER

John J. Kurtz, St. Louis, Mo.

Application May 27, 1958, Serial No. 51,096

Term of patent 3½ years

(Cl. D81—10)

FIG. 1.

FIG. 2.

FIG. 3.

Fig. 1 is a top plan view of a butter warmer embodying my new design;

Fig. 2 is a side elevational view, and

Fig. 3 is a side elevational view, showing the butter warmer.

I claim:

The ornamental design for a butter warmer, substantially as shown.
